PORTABLE DESK AND LIGHT COMBINATION

Horace J. Taylor, 349 N. Homan Ave.,
Chicago, Ill. 60624

Filed Aug. 15, 1967, Ser. No. 8,268

Term of patent 14 years

(Cl. D33—7)

I claim:

The ornamental design for a portable desk and light combination, as shown.
